UNITED STATES PATENT OFFICE.

CHARLES W. BECK, OF NEW YORK, N. Y., ASSIGNOR, BY MESNE ASSIGNMENTS, TO ELECTROLITE GAS LAMP COMPANY, OF NEW YORK, N. Y.

ACETYLENE-GAS-GENERATING LAMP.

SPECIFICATION forming part of Letters Patent No. 790,275, dated May 23, 1905.

Application filed October 13, 1900. Serial No. 32,973.

To all whom it may concern:

Be it known that I, CHARLES W. BECK, of New York, county of New York, and State of New York, have invented certain new and useful Improvements in Acetylene-Lamps, of which the following is a specification.

This invention relates to improvements in acetylene-lamps, and refers more specifically to a lamp of that type wherein the carbid in granulated or pulverulent form is fed to a body of water in graduated quantities automatically controlled by the pressure of gas generated and consumed, the particular embodiment of the invention shown herein consisting of a portable table-lamp or lamp for domestic and analogous purposes.

Among the objects of the present invention are to provide improvements in the construction and arrangement of the lamp contributing to produce an efficient and compact device of artistic form; to so construct and arrange the parts that a maximum capacity is provided for containing the liquid, the carbid, and the operative parts, the carbid-feeding mechanism being arranged at a sufficient height above the liquid to insure most satisfactory results, while at the same time that part of the lamp which unites the carbid-receptacle with the font or water-reservoir is of minimum dimensions; to provide improvements in the details of construction of the expansible gas-holder and the tension mechanism whereby the inflation of said holder is resisted; to provide improvements in the details of construction and arrangement of a reducing-valve interposed between the expansible gas-holder and burner-nozzle, contributing to the uniformity of pressure at the burner; to provide improved mechanism for locking the feed mechanism in closed position, and in general to provide simplified and improved details of construction and arrangement contributing to the economy of manufacture, efficiency of operation, and convenience of use of the lamp.

To the above ends the invention consists in the matters hereinafter described, and more particularly pointed out in the appended claims, and the same will be readily under-

stood from the following description, reference being had to the accompanying drawings, in which—

Figure 1 is an axial vertical sectional view, with parts in side elevation, of a lamp forming a preferred embodiment of my invention. Fig. 2 is a fragmentary detail plan view of parts of the locking mechanism whereby the feed mechanism is locked against operation.

Referring to said drawings, 1 designates as a whole the font or water-reservoir, constituting in the present instance the base portion of the lamp and desirably comprising a cylindric lower portion 2, provided with a convex top and portion 3, which terminates at its upper end in a cylindric rim 4.

5 designates as a whole the upper member of the lamp, which is adapted to be detachably united with the font or base portion, said upper member comprising a bowl-shaped upper portion 6, united with and supported upon a contracted waist portion 7, the lower end of which terminates in a cylindric rim 8 of equal size and similar to the rim 4 and adapted to rest upon the latter. Between said meeting rims is formed a circumferential groove 9, within which is arranged a packing-ring 10, adapted to be compressed when the upper and lower members are secured together, so as to form a gas-tight joint. As a convenient means for thus uniting the upper and lower members the rim of the font is provided with an upstanding eye 10', adapted to be engaged by a radially-extending and upwardly-curved hook 11 upon the rim of the upper member, and at a point diametrically opposite said hook and eye the rim of the font is provided with a pivoted link 12, adapted to engage a lug 13, located upon the rim of the upper member at a point in register with the plane of the vertical movement of the link, so that the latter may be engaged therewith, as indicated clearly in the drawings. In order to draw the upper member downwardly into clamped engagement with the lower member, the upper side of the eye 10' is so located that when its hook is engaged therewith and the upper member forced downwardly this side of the packing-ring will be

brought under compression, and in order to similarly compress the opposite side of the packing-ring the end of the link which engages the stud 13 is provided with a thumb-screw 12', threaded therethrough and adapted to impinge upon the upper side of the stud, and thus draw the two members together.

The waist portion 7 of the lamp is desirably constructed with the concave or inwardly-curved sides shown, this construction having the advantage not only of presenting a neat and graceful appearance, but at the same time of reducing the gas-space within said waist to a minimum. The inner side of the wall of this contracted gas-chamber or waist portion inclines upward and inward to a point just below the bottom of the carbid-hopper and contracts the gas-space between the base or water-holder and the carbid-holder, said chamber at its most contracted point being just large enough to permit the carbid from the feeding mechanism to drop through without contacting with the walls of the contracted chamber. The purpose of thus contracting this chamber to the utmost consistent with the proper operating of the lamp and of inclining inward and upward the walls of the chamber are fourfold—first, to cause the upward-moving gas to contact with the walls, and thereby condense a considerable portion of the moisture, which is carried upward by the hot gas; second, to reduce to a minimum the air in the lamp when the generation of gas is first begun; third, to form a standard-like handle between the water-holder and the carbid-holder, which may be grasped when it is desired to lift the lamp, and, fourth, to permit the gas-tight joint between the two parts to be made at the reduced part of the casing, the advantages of which are evident.

The carbid-receptacle 6, which is mounted upon the waist portion, has its downwardly-converging sides prolonged or extended inwardly beyond the junction with the waist portion, as indicated at 14, to form a partition separating the carbid-chamber from the gas-space beneath the latter, the lower end of said hopper terminating in a feed-opening 15, through which is arranged to work a feed-plunger 16.

Describing now more particularly the feed mechanism, 17 designates a cylindric ring mounted upon the under side of the carbid-hopper concentric with the feed-aperture thereof and forming, in conjunction with the under side of said hopper, a cup-shaped receptacle, within which is mounted a rubber diaphragm or ring 18, through which works the feed-plunger 16. In order to reduce to a minimum the rubbing friction between the inner periphery of the ring and the sides of said feed-plunger, the inner margin of the ring is brought to a blunt edge, as indicated clearly in the drawings, and in order that the size of the opening through the ring may be

reduced from time to time to compensate for wear and insure a close-rubbing joint between the diaphragm and the feed-plunger means are provided for compressing the ring, conveniently and as shown herein consisting of a cap 19, threaded upon the housing-ring 17, having its lower end constructed to underlie and bear upon the lower surface of the rubber ring and provided with a central aperture 20 of sufficient diameter to prevent interference with the operation of the plunger. The plunger 16 in the preferred construction shown herein is provided with a cylindric lower portion 21, which normally during the operation of the lamp rests within or is in register with the diaphragm-ring 18, a reduced portion 22 immediately above said cylindric portion, and a second cylindric portion 23 of the same diameter as the lower cylindric portion, which is arranged to be brought into register with the diaphragm-ring when the plunger is at its lowermost position or that indicated in the drawings. The upper end of the lower cylindric portion 21 at its point of junction with the reduced portion 22 is made conical or tapering upwardly, as indicated at 24, so as to act as a deflector to disperse the carbid as it flows downwardly past the plunger.

Within the upper part of the carbid-hopper is formed a chamber, (designated as a whole 25,) the lower portion of said chamber being formed by means of a cup-shaped partition 26, having its upper edge 27 joined with the top wall of the lamp, while the upper portion of said chamber is formed by the dome-shaped top wall 28 of the extreme upper end of the lamp. The lower side of the chamber thus formed is provided with a central aperture 29, which opens into a downwardly-dependant tubular extension or housing 30, which extends downwardly to a point near the lower end of the carbid-hopper, but terminates far enough above the feed-opening through the latter to permit the flow of carbid to said opening past its lower end. Within the chamber 25 is arranged an expansible gas-holder of novel and improved construction comprising a lower cup-shaped metal member 31, provided at its center with an orifice in register and communication with the tubular extension 30, said cup-shaped member being secured to the bottom wall of the chamber desirably and as shown herein by means of a hollow screw-plug 32, extended downwardly through the central aperture of the cup-shaped member and threaded into the interior of the upper end of said tubular housing, so as to clamp said parts together. Desirably, in order to form a gas-tight union at this point, a packing-washer 33 is interposed between the under surface of the gas-holder and the bottom wall of the chamber. The upper portion 31' of said gas-holder is made flexible, so as to enable the gas-holder to expand, this portion consisting, preferably, of a sheet of rubber secured at its periphery to

the exterior of the upper rim of the cup-shaped member by means of a confining-ring 34. Upon the upper surface of said flexible sheet is mounted a rigid disk 35, and through this disk and the subjacent portion of the flexible sheet is arranged to extend a hollow nipple 36, with the upper end of which is connected a flexible length of tubing 37, having its opposite end connected to and communicating with a reducing-valve mounted in the upper part of said chamber and designated as a whole 38.

The stem 39 of the feed-plunger is arranged to extend axially up through the tubular extension 30 and through the upper side of the gas-holder and is made rigid with the disk 35 thereof, conveniently and as shown herein by means of upper and lower clamping-washers 40 41, respectively, threaded upon the stem 20 of the feed-plunger and clamping between them the interposed disk and underlying flexible sheet of the gas-holder.

42 designates a coiled contractile spring arranged within the tubular extension, having its upper end engaged with the upper end of the stem of the plunger, so as to tend to draw the latter downwardly, and the lower end engaged with a collar 43, seated in the lower portion of the extension and held against upward movement by means of an internal flange 44 upon the interior of the extension with which the periphery of the collar is engaged.

Describing now more particularly the construction of the reducing-valve 38, the latter is supported by means of a spider consisting of a ring 43', secured to the interior of the chamber 25, and a plurality of radial arms 43", which extend from said ring obliquely upward to and support the valve-body proper. The valve-body comprises a lower cylindric chamber formed of two members 45 46, respectively, threaded together, said chamber being divided horizontally by means of a filtering-diaphragm 47, held at its edges between the meeting parts of the two members, as indicated clearly in the drawings. The flexible gas-tube 37 communicates with the space below said diaphragm. The upper wall of said chamber is provided with a gas-port 48, communicating with an upper chamber 49, the upper side of which is formed by means of a flexible diaphragm 50, which is held distended and secured at its edges, so as to form a gas-tight chamber by means of a skeleton-shaped member 51, having a peripheral ring portion 52, which is secured to the subjacent member 46 in any convenient manner—as, for example, by screws 53. Said skeleton member 52 is provided with a plurality of arms 54, constructed to fit against the upper wall of the chamber 25 and suitably secured to the latter, one of said arms being made hollow or provided with a passage 55, which communicates at its lower end with the gas-space beneath the diaphragm and at its upper

end terminates in a threaded nipple 56, upon which is mounted the burner-nozzle 57.

58 designates a valve arranged to control the gas-port 48 of the reducing-valve, said valve being provided with a stem extending 70 upwardly through and being connected with the center of the diaphragm 50 by means of suitable clamping-washers mounted thereon above and below the diaphragm, respectively. In order to force the valve normally downward away from its seat, a spring is arranged to act upon the upper side of the diaphragm, such spring consisting desirably of a V-shaped spring secured at its angle to one of the arms of the member 54, as at 58, and having one 80 of its arms engaged with the center of the diaphragm, while its opposite arm rests in engagement with an adjusting-screw 59, threaded through the top wall of the lamp and through the subjacent arm 54. 85

It will be noted that the part 45 of the filter-support will form an upper stop for the diaphragm or movable upper portion 31' of the gas-holder. The upper end of the valve-rod will contact with said part 45 when the 90 gas-holder is expanded and will limit the upward movement of the diaphragm and the plate 35 will form a support for the diaphragm and prevent an undue expansion thereof. The nipple connecting the tubular extension 30 to 95 the cup 26 will form a stop for the diaphragm and limit the downward movement of the valve, and the lower wall 31 will form a support for the diaphragm when it is completely collapsed. 100

Means are provided for locking the feed mechanism against movement, such means preferably comprising a double bell-crank lever 60, (see detail Fig. 2,) pivotally supported adjacent to its angle to a support upon the 105 side wall of the chamber 25, as indicated at 61. One arm 60' is preferably made double and arranged to extend obliquely downward and engage the center of the upper side of the expandible gas-holder, the engaging lower ends of the members of the arm being curved upwardly, so as to slide freely during the rising-and-falling movement of the gas-holder. In order to engage said arm 60' with the feed-plunger, so that it may be caused to lift the 115 latter, a cross-piece 60" is mounted upon the extreme upper end of the plunger with its arms arranged to overlie the two members of the double arm 60', as indicated clearly in said detail figure. At a point between its 120 ends said double arm is provided with an up-standing rigid block or stud 62, constituting the second arm of the bell-crank lever, which is adapted to be engaged by a thumb-screw 63, arranged to extend inwardly through the 125 opposite side of the wall of the chamber 25 and threaded through the lower part 45 of the reducing-valve, as shown clearly in the drawings, the arrangement being such that when 130 said adjusting-screw is adjusted inwardly the

feed-plunger will be lifted to its uppermost limit, so as to bring its cylindric lower portion 21 in register with the diaphragm-ring and locked in this position.

5. In order to convey the gas from the gas-space below the carbid-hopper to the upper part of the latter, a pipe 64 is arranged to communicate at its lower end with an opening 65 in the bottom of the hopper and extends 10 thence upwardly along the inner wall of the hopper to a point near the upper side of the latter, at which point it communicates with the chamber 66 of a safety-valve, (designated as a whole 65'). The upper end of the pipe 64 is provided with one or more openings 67, through which the gas may escape into the upper part of the carbid-hopper, and from the space within the hopper the gas is admitted to the upper part of the tubular extension 30 15 through a plurality of inlet-openings 68.

The safety-valve 65' may be of any suitable or preferred construction, that shown herein consisting of a puppet-valve 69, held against its seat by means of a coiled spring 70, the 20 opposite end of which engages an adjusting-cap 71, through which are provided vent-openings 72.

- The operation of the apparatus constructed as described will be readily understood by 30 those skilled in the art from the foregoing description, but may be briefly described as follows: The font and hopper having been respectively charged with suitable quantities of water and carbid while the feed-plunger was held in locked position, the apparatus may be 35 brought into operation by simply rotating the thumb-screw of the locking mechanism, so as to release the plunger, whereupon the latter will be forced downwardly by the feed-spring 40 and permit the granulated carbid to flow outwardly through the diaphragm-ring past the reduced portion 22 of the feed-plunger. The carbid falling within the water in the font will promptly generate a supply of gas, which 45 rising within the generating-chamber will pass upwardly through the tube 64 into the upper part of the hopper and in passing over the body of carbid will be cooled and dried. From 50 the carbid-hopper the gas passes inwardly through the inlets in the tubular extension and thence upwardly into the expandable gas-holder, inflating the latter and eventually raising the plunger far enough to interrupt the feeding of carbid. From the gas-holder the 55 gas passes upwardly through the flexible tube 37 into the reducing-valve through the filtering-diaphragm of the latter and thence to the upper chamber, from whence it passes upwardly to the burner-nozzle. Inasmuch as 60 the feed-spring of the feed mechanism exerts an increasing pressure on the gas-holder as the latter is inflated more and more, the internal gas-pressure within the holder is correspondingly increased and would tend to make 65 the pressure at the burner irregular but for

the provision of the reducing-valve. The reducing-valve, however, is so adjusted that as the pressure within its upper chamber increases the diaphragm thereof will be forced upwardly against the tension of the V-spring, 70 thereby partially closing the port between the two chambers of the valve and correspondingly restricting the flow of gas to the burner, thus substantially counterbalancing the increased pressure within the generator. 75

The provision of the upper cylindric portion of the feed-plunger 23 is a feature of importance, for the reason that if the gas-holder should burst or spring a leak or the mechanism in any way become disarranged so as to 80 permit the plunger to drop and not respond to the generation of gas the plunger would obviously fall to its lowermost position, or that indicated in the drawings, in which position the port 23 would act as a stopper to effectually close the feed-opening of the hopper. The provision of locking mechanism whereby the plunger may be locked in closed position is also of importance not only for the reason that it forms a convenient means of interrupting the operation of the generator at will, but for the further reason that when thus locked in closed position the liquid could not reach the interior of the carbid-chamber in case the lamp were instantly overturned except 95 through the restricted gas-inlet ports in the upper part of the hopper, and an explosion could therefore not occur. When the lamp has been operated long enough to make it necessary to replenish the supply of liquid or to 100 remove the residue from the font, this may readily be accomplished by separating the upper and lower members of the lamp in the manner hereinbefore clearly described.

While I have herein shown and described 105 what I deem to be a preferred embodiment of my invention, yet it will be obvious that the details thereof may be modified to some extent without departing from the invention, and I do not, therefore, wish to be limited to the precise details shown except as they are made the subject of specific claims.

I have not specifically claimed in this application features shown which constitute a generator proper, as said features will be claimed 115 in another copending application.

I claim as my invention—

1. In an acetylene-lamp the combination of the lower part which constitutes the lamp-base and water-holder, the upper part which forms a carbid-holder, a gas-holder smaller in diameter than the carbid-holder and concentrically supported within and near the top thereof said gas-holder having a movable wall or part, a depending feed mechanism carried by the upper part, means for connecting said feed mechanism to the movable part of the gas-holder, a burner carried by the upper part of the case, a pressure-regulator within the case at the top of the upper part and in com- 125

munication with the gas-holder and the burner, and means for detachably connecting the two parts together at the top of the base portion.

2. In an acetylene-lamp, the combination of a two-part casing, adapted to be detachably secured together one part above the other, the lower part being formed with a contracted upper end and constituting the water-holder and the lamp-base the upper part being formed with a carbid-hopper and a depending contracted gas-chamber, a cup-shaped chamber supported in the carbid-hopper, a gas-holder in said chamber said holder having a movable wall or part, a feed mechanism connected to said movable part and arranged to feed carbid through said contracted chamber to the water-holder, means for detachably connecting the lower edge of the contracted gas-chamber to the contracted upper part of the water-holder, whereby the gas-chamber will form a standard-like handle and a narrow gas-space between the water-holder and the carbid-holder, and the gas-tight joint will be formed at the reduced part of the casing, a burner carried by the upper part of the casing and a pressure-regulator in communication with the gas-holder and the burner.

3. In an acetylene-lamp, the combination of a lower water-holder formed with a connecting-ring at its upper end smaller in diameter than the water-holder, an upper carbid-holder, an intermediate contracted gas-chamber permanently secured to the carbid-holder, means for detachably connecting the lower edge of this contracted chamber to the connecting-ring on the top of the water-holder whereby the contracted chamber forms a standard-like handle for the lamp and a contracted gas-space between the water-holder and the carbid-hopper and the gas-tight connection will be formed at the reduced part of the casing, a cup-shaped chamber smaller in diameter than the carbid-holder and supported in the upper part of said holder, a gas-holder in said chamber said holder having a movable wall or part, a feed mechanism connected to and operated by said movable part and adapted to drop pulverized carbid centrally through the contracted chamber, a burner carried by the carbid-hopper, and a reducing-valve within the casing and in communication with the gas-holder and burner.

4. In an acetylene-lamp, the combination of a lower water-holder formed with a connecting-ring at its upper end smaller in diameter than the water-holder, an upper carbid-holder, an intermediate contracted gas-chamber permanently secured to the carbid-holder, the inner sides of the walls of the said chamber inclining from their lower edge inward and upward to a point near the bottom of the carbid-hopper, whereby the upward-flowing gas in said chamber will contact therewith and the moisture therein be condensed on said walls, means for detachably connecting the

lower edge of this contracted chamber to the connecting-ring on the top of the water-holder whereby the contracted chamber forms a standard-like handle for the lamp and a contracted gas-space and condenser between the water-holder and the carbid-hopper and the gas-tight connection will be formed at the reduced part of the casing, a cup-shaped chamber smaller in diameter than the carbid-holder and supported in the upper part of said holder, a gas-holder in said chamber said holder having a movable wall or part, a feed mechanism connected to and operated by said movable part and adapted to drop pulverized carbid centrally through the contracted chamber, a burner carried by the hopper, and a reducing-valve within the casing and in communication with the gas-holder and burner.

5. In an acetylene-lamp, the combination of a casing, the lower part of which forms a water-holder, the upper part forming a carbid-holder, a cup-shaped chamber smaller in diameter than the carbid-holder and concentrically supported in the upper part of said holder, a gas-holder in said chamber said holder having a movable wall or part, a feed mechanism connected to and operated by said movable part, a burner on the top of said chamber, and a reducing-valve within the casing, and in communication with the gas-holder and burner.

6. In an acetylene-lamp, the combination of a casing, the lower part of which holds one gas-generating element, the upper part forming a holder for the other element, a chamber or receptacle smaller in diameter than the casing and concentrically supported in the casing at the top thereof, an expansible gas-holder in said chamber, feeding mechanism adapted to feed the element in the upper part of the casing, said feeding mechanism being connected to and operated by the expansible holder, a burner on the casing, and a pressure-regulator above the case-holder and in communication with the gas-holder and the burner.

7. In an acetylene-gas lamp, the combination of a lower part which constitutes a holder for the liquid and forms the lamp-base, an upper part, said upper part being concentrically mounted on the top of the base and constituting a carbid-holder, a receptacle smaller in diameter than the carbid-holder and concentrically supported in the casing at the top thereof, said receptacle extending down into the carbid-hopper and carrying the feeding mechanism, a pressure-regulator above the feeding mechanism and a burner above the pressure-regulator.

8. In an acetylene-lamp, the combination of a lower part which constitutes a holder for the liquid and forms the lamp-base, an upper part concentrically mounted on the top of the base and detachably connected thereto, said upper part forming a holder for the carbid, a cup-shaped receptacle smaller in diameter than the

carbid-holder and secured at its upper edge to the top of the carbid-holder and extending down into said holder, said cup-shaped receptacle being concentrically located therein, an 5 expandible gas-holder in the said cup, a depending feed mechanism centrally connected to the upper wall of said gas-holder and operated thereby, a reducing-valve supported above the cup, said valve being in communication with the gas-holder, and a burner supported above the reducing-valve and in communication therewith.

9. In an acetylene-gas lamp, the combination of a lower part which constitutes a holder 15 for the liquid and forms the lamp-base, an upper part concentrically mounted on the top of the base and detachably connected thereto, said upper part forming a holder for the carbid, a cup-shaped receptacle smaller in diameter than the carbid-holder and secured at its upper end to the top of the upper part and extending down into the carbid-holder, said cup-shaped receptacle being concentrically located in the carbid-holder, an expandible gas-holder 20 in the said cup, depending feed mechanism concentrically connected to the upper wall of said gas-holder and operated by the movement of said wall, a horizontally-movable rod above the cup, and means carried by the cup and engaging 25 the top of the gas-holder to manually extend said holder when the rod is moved horizontally in one direction, a reducing-valve supported centrally above the cup and carrying 30 said rod, a burner supported by the casting and in communication with the reducing-valve.

10. In an acetylene-lamp, the combination of a lower part which constitutes a holder for the liquid and forms the lamp-base, an upper 40 part concentrically mounted on the top of the base and detachably connected thereto, said upper part forming a holder for the carbid, a cup-shaped receptacle smaller in diameter than the carbid-holder and secured at its upper edge to the top of and extending down into said holder, said cup-shaped receptacle being concentrically arranged in the carbid-holder, an expandible gas-holder in the said cup, a depending feed mechanism centrally connected 45 to the upper wall of said gas-holder and operated by the movement thereof, a ring supported at the top of said cup, a reducing-valve above the cup and supported by said ring, and a burner carried by the reducing-valve.

55 11. In a gas generator or lamp, tanks or chambers for separately holding gas-generating elements, a passage from one to another, a valve between them, an expandible and collapsible gas-chamber in communication with the gas-space in said tanks, said valve being connected with said expandible and collapsible gas-chamber in such manner that when the latter is expanded the passage from one said tank or chamber to the other is closed, a lever 60 in engagement with said collapsible gas-chamber

and adapted to move therewith, and a screw arranged for acting upon said lever, and means for causing said gas-chamber to move with the lever whereby, on the operation of the screw in one direction the gas-chamber is expanded and the light extinguished. 70

12. In a gas generator or lamp, tanks or chambers for separately holding gas-generating elements, a passage from one to another, a valve between them, an expandible and collapsible gas-chamber in communication with the gas-space in said tank, said valve being connected with said expandible and collapsible gas-chamber in such manner that when the latter is expanded the passage from one said tank or chamber to the other is closed, a lever in engagement with said collapsible gas-chamber and adapted to move therewith, and mechanism for adjusting said lever. 75

13. In a gas generator or lamp, tanks or chambers for separately holding gas-generating elements, a passage from one to another, a valve between them, an expandible and collapsible gas-chamber in communication with the gas-space in said tanks, said valve being connected with said expandible and collapsible gas-chamber in such manner that when the latter is expanded the passage from one said tank or chamber to the other is closed, a lever in engagement with said collapsible gas-chamber and adapted to move therewith and a screw 80 90 95 arranged for adjusting said lever.

14. In an acetylene-generator adapted to feed pulverulent carbid and comprising a carbid-hopper provided at its lower side with a feed-opening, a feed-plunger working through said opening and having a stem extending upwardly within said carbid-hopper, means for locking said plunger against movement, comprising a bell-crank lever having one arm flexibly connected with the upper end of said plunger and pivotally supported adjacent to its angle from the side wall of the generator and an adjusting-screw extending inwardly through the side wall of the generator through a threaded support and engaging the other arm of said bell-crank lever. 100 105 110

15. In an acetylene-generator, the combination with the reciprocating feed-plunger 115 operatively connected at its upper end with the expandible gas-holder, of means for locking said plunger against movement, comprising the bell-crank lever pivotally mounted adjacent to its angle and having arms one engaged with the cross-bar upon the upper end of the plunger, and an adjusting-screw extending inwardly through the side wall of the generator and threaded through a support and acting upon the other. 120

16. A gas-generator including chambers for separately holding gas-generating elements, a gas-holder reservoir of variable capacity in communication with one of said chambers, a pivoted lever, one end of said lever being en- 125 130

gaged to move with a movable wall of said reservoir, and an adjusting-screw coacting with said lever for forcibly distending said reservoir.

- 5 17. A gas generator or lamp including tanks or chambers for separately holding gas-generating elements and having a passage from one chamber to the other, a valve for controlling said passage, a gas-reservoir of variable 70 capacity situated above said chambers, a valve-rod secured to the top wall of said reservoir and by means of which said valve is controlled to move up and down with the increase or decrease of capacity of said reservoir, and a lever 15 in engagement with the upper wall of said reservoir adapted to move therewith, and manually-controlled means for coacting with said lever for forcibly distending said reservoir.

18. A carbid-feed lamp comprised of a casting the lower part of which forms a water-holder, the upper part carrying a carbid-holder, carbid-feed mechanism in said upper part, an expansible gas-holder connected to and operating the feed mechanism, a burner 25 carried by the casing, means automatically operating to maintain a uniform burning pressure at the burner, said means being in communication with the gas-holder, and means for adjusting the pressure-regulating means 30 to vary the burning pressure.

19. In a gas generator or lamp, tanks or chambers for separately holding gas-generating elements, a passage from one to another, a valve between them, an expansible and collapsible gas-chamber in communication with the gas-space in said tank, said valve being connected with said expansible and collapsible gas-chamber in such manner that when the latter is expanded the passage from one tank 40 or chamber to the other is closed, a lever in engagement with said collapsible gas-chamber and adapted to move therewith, and a screw arranged for acting upon said lever for expanding the gas-chamber to extinguish the lamp.

20. A gas-generator including chambers for separately holding liquid and pulverulent gas-generating elements and having a passage from one chamber to the other, a valve coöperating with the communicating passage, a gas-holding reservoir of variable capacity, a portion of the wall of the reservoir being movable, the gas generated passing through said reservoir, said valve being connected to the 55 movable wall portion of the reservoir so as to be moved therewith, a lever mounted to move with either said valve or the movable portion of said reservoir, and mechanism for adjusting said lever.

21. A gas-generator including chambers for separately holding liquid and pulverulent gas-generating elements and having a passage from one chamber to the other, a valve coöperating with the communicating passage, a 60 gas-holding reservoir of variable capacity, a

portion of the wall of the reservoir being movable, the gas generated passing through said reservoir, said valve being connected to the movable wall portion of the reservoir so as to be moved therewith, a lever mounted to 70 move with either said valve or the movable portion of said reservoir, and adjustable mechanism for forcibly distending the movable wall of the reservoir.

22. A gas-generator including separate 75 holding-chambers for liquid and pulverulent gas-generating elements, a collapsible gas-reservoir of variable capacity situated above said chambers and in communication with one of said chambers whereby the gas generated 80 may pass into said reservoir, a valve coacting with a passage between said chambers and movable as the reservoir varies in capacity, and manually-controlled means coöperating with said reservoir to forcibly and positively 85 distend it.

23. In a gas generator or lamp, chambers for separately holding gas-generating elements, a passage from one of said chambers to the other, a vertically-reciprocatory valve controlling 90 said passage, a lever, operative connections between said lever and the valve, and a device coacting with said lever to check its movement.

24. In a gas-generator, chambers for separately holding gas-generating elements, a passage from one of said chambers to the other, a vertically-reciprocatory valve controlling said passage, an adjustable lever, operative 95 connections between said lever and the valve 100 whereby the valve may be operated through the lever.

25. In a gas-generator, chambers for separately holding gas-generating elements, a gas-holder reservoir of variable capacity above 105 the carbid-chamber and in communication with one of said chambers, a valve controlling the passage of carbid into the generating-chamber, a lever in engagement with said gas-reservoir, and adapted to move therewith, and 110 means for locking said lever.

26. In a gas-generator, chambers for separately holding gas-generating elements, a passage from one of said chambers to the other, a valve controlling said passage, a lever, operative 115 connections between said lever and the valve and an adjustable stop for limiting the movement of said lever.

27. In an acetylene-gas generator, chambers for separately holding gas-generating elements, a passage from one of said chambers to the other, an elastic valve ring or seat in said passage, a valve working through said valve-ring and fitting closely therein and controlling the discharge of carbid therethrough, 120 means for moving said valve in response to changes in gas-pressure, a lever connected to said valve, and means for locking said lever to maintain the valve closed.

28. In a gas-generator, chambers for sepa- 125

rately holding gas-generating elements, a passage from one of said chambers to the other, an elastic valve ring or seat in said passage, a plunger-valve working through said valve-ring and controlling the discharge of carbid, a lever, operative connections between said lever and the valve and mechanism for adjusting said lever.

29. In a gas-generator, chambers for separately holding gas-generating elements, a passage from one of said chambers to the other, an elastic valve-ring in said passage, a plunger-valve working through said ring, a lever, operative connections between said lever and the valve, and an adjustable stop for locking said lever to positively hold the valve in its closed position.

30. In an acetylene-gas generator a generating-chamber, a carbid-holder above the generating-chamber and formed with a feed-opening in its bottom, a housing in the holder axially in line with the feed-opening and open at its lower end, said lower end extending near to the feed-opening, a vertically-reciprocating valve extending into the holder and controlling the feed-opening and of smaller diameter than the interior of the housing, and means controlled by the pressure of the gas generated to reciprocate said valve in the housing.

31. In an acetylene-gas generator, a generating-chamber, a carbid-holder above the generating-chamber and formed with a feed-opening in its bottom, a housing in the holder axially in line with the feed-opening and open at its lower end, said lower end extending near to the feed-opening, a vertically-reciprocating valve extending into the holder and controlling the feed-opening said valve being of smaller diameter than the interior of the housing, means controlled by the pressure of the gas generated to move said valve, a lever, operative connections between the lever and the valve whereby the valve may be manually reciprocated in the tubular housing and said housing will protect the valve from the mass of carbid in the hopper.

32. A carbid-feed mechanism for acetylene-gas generators, comprising a carbid-holder provided with a discharge-opening, a feed-plunger working through said opening and formed with two rigid valve members rigidly connected together and separated longitudinally, whereby a pocket is formed between them, a tubular housing within the holder and slightly above the feed-opening and open at its lower end, and adapted to receive the upper feed member, means for reciprocating said valve whereby the upper valve member will force the carbid in the pocket downward through the feed-opening.

33. A carbid-feed mechanism for acetylene-gas generators comprising a carbid-holder provided with a discharge-opening, a feed-plunger working through said opening and

formed of two rigid valve members rigidly connected together and separated longitudinally whereby a pocket is formed between them, a tubular housing within the holder slightly above the feed-opening and open at its lower end and adapted to receive the upper valve member, means actuated by the pressure of the gas to move the valve and carry the upper member into the housing, and means acting against gas-pressure to move the valve and carry the upper valve member below said housing to force the carbid in the pocket downward through the feed-opening.

34. In an acetylene-gas generator tanks or chambers for separately holding gas-generating elements, a passage connecting said tanks, a valve controlling said passage, an expandible and collapsible gas-chamber in communication with the gas-space in said tanks, said valve being connected with said expandible and collapsible gas-chamber in such manner that when the latter is expanded the passage between the tanks is closed, an operating-screw, and means interposed between the screw and the expandible gas-chamber whereby said chamber may be positively expanded by the screw to close the passage between the tanks.

35. In an acetylene-gas generator the combination of chambers for separately holding gas-generating elements, a feed-passage connecting said chambers, a valve controlling said feed-passage, an expandible and collapsible gas-holder, means whereby said holder by its expansion and contraction will move the feed-valve, an adjusting-screw, and means interposed between the screw and the valve whereby said valve may be positioned by the screw.

36. In a gas generator or lamp chambers for separately holding gas-generating elements, a passage from one of said chambers to the other, a valve controlling said passage, an adjustable lever, operative connections between said lever and the valve whereby the valve may be operated through the lever, and means normally permitting said lever to swing freely on its pivot but adapted to be adjusted to check the movement of said lever.

37. In a gas generator or lamp chambers for separately holding gas-generating elements, a passage from one of said chambers to the other, a valve controlling said passage, an adjustable lever, operative connections between said lever and the valve whereby the valve may be operated through the lever, and means for locking said lever in its adjusted position.

38. In an acetylene-gas generator the combination of chambers for separately holding gas-generating elements, a feed-passage connecting said chambers, a valve controlling said feed-passage, an expandible and collapsible gas-holder, means whereby said holder by its expansion and contraction will move the feed-valve, an adjusting-screw, and means interposed between the screw and the valve where-

by the feed of carbid may be manually stopped or started.

39. In an acetylene-gas lamp the combination of a lower part which constitutes a holder for the liquid and forms the lamp-base, an upper part concentrically mounted on the top of the base and detachably connected thereto said upper part forming a holder for the carbid, a part secured at its outer edge to the carbid-holder near the top thereof and extending into said holder a suitable distance to form a support for a gas-holding wall, said part being concentrically mounted in the carbid-holder, a transverse horizontal flexible gas-holder wall carried by said concentric support, a depending feed mechanism centrally connected to said movable wall or part and operated thereby, a reducing-valve supported above the gas-holder wall said valve being in communication with the gas-space below the wall, and a burner supported above the reducing-valve and in communication therewith.
40. In an acetylene-gas generator the combination of a three-part generator-casing comprising a base or water-holder, an intermediate section detachably connected thereto and which forms the carbid-holder and within which is arranged the feed-plunger, and an upper chamber supported by the carbid-holder, a flexible diaphragm at the bottom of said upper chamber and subject on its under side to the gas-pressure in the carbid-holder, means operatively connecting said diaphragm to the feed-plunger whereby said plunger will be moved in response to gas-pressure, a pressure-regulator in the upper chamber above the flexible diaphragm, means for placing said pressure-regulator in communication with the gas-space below the flexible diaphragm, and a burner above the pressure-regulator and in communication therewith, an operating-screw, and means connected to said screw whereby the feed of carbid may be manually stopped or started.

regulator in the upper chamber above the flexible diaphragm, a stationary support in said upper chamber for said regulator, means for placing said pressure-regulator in communication with the gas-space below the flexible diaphragm, and a burner above the pressure-regulator and in communication therewith.

41. In an acetylene-gas generator the combination of a three-part generator-casing comprising a base or water-holder, an intermediate section detachably connected thereto and which forms the carbid-holder and within which is arranged the feed-plunger, and an upper chamber supported by the carbid-holder, a flexible diaphragm at the bottom of said upper chamber and subject on its under side to the gas-pressure in the carbid-holder, means operatively connecting said diaphragm to the feed-plunger whereby said plunger will be moved in response to gas-pressure, a pressure-regulator in the upper chamber above the flexible diaphragm, means for placing said pressure-regulator in communication with the gas-space below the flexible diaphragm, and a burner above the pressure-regulator and in communication therewith, an operating-screw, and means connected to said screw whereby the feed of carbid may be manually stopped or started.
